Des. 239,557
Patented Apr. 13, 1976

239,557

LANTERN

Thomas H. Nicholl, 1204 W. 27th St.,
Kansas City, Mo. 64108

Filed Aug. 19, 1974, Ser. No. 498,743

Term of patent 14 years

Int. Cl. D26—02

U.S. Cl. D48—24 R

Fig. 3.

Fig. 2.

Fig. 4.

Fig. 7.

Fig. 5.

Fig. 6.

FIG. 1 is a perspective view of a lantern embodying my design.

FIG. 2 is a side elevational view thereof, the opposite side being a mirror image of the side shown.

FIG. 3 is a rear elevational view thereof.

FIG. 4 is a front elevational view thereof.

FIG. 5 is a top plan view thereof.

FIG. 6 is a bottom plan view thereof.

FIG. 7 is a side elevational view thereof showing the lantern in an upright position.

I claim:

The ornamental design for a lantern, as shown and described.
